UNITED STATES PATENT OFFICE.

HENRY OLIVER, OF NEW YORK, N. Y.

PARTITION AND WALL-FURRING.

1,023,526.

Specification of Letters Patent. Patented Apr. 16, 1912.

Application filed April 20, 1909. Serial No. 491,114.

To all whom it may concern:

Be it known that I, HENRY OLIVER, a citizen of the United States, residing in the city of New York, borough of Manhattan, county and State of New York, have invented certain new and useful Improvements in Partitions and Wall-Furriings, of which the following is a full, clear, and exact specification.

10 My invention relates to improvements in the construction of partitions for walls, and it is also applicable to the construction of furriings, etc.

It has for its object to facilitate the quick 15 and inexpensive construction thereof, and particularly to provide for the construction of portable elements of such partition, etc., and their easy assembling into a finished partition, etc., and to insure an adequate air 20 space within the partition, etc., as well as providing ample space for the reception of seam and water pipes or others, and also electric wire conduits.

25 My invention consists in the parts and combination of parts hereinafter described and more particularly illustrated in the accompanying drawings, wherein—

Figure 1 is a vertical cross-section of a 30 partition embodying my invention. Fig. 2 is a longitudinal section of the same. Fig. 3 is a side elevation of the same, with part of the wire mesh and lath and likewise part of the plaster coating removed. Fig. 4 is a detail in perspective, illustrating 35 the internal construction of partition.

While I have illustrated my invention in Fig. 1 as employed in the production of a hollow partition, it is not necessarily limited thereto.

40 The partition (Fig. 1), is composed of the longitudinal upper and lower plate-pieces 1, 2, of wood or suitable sheet iron channels or clips. These are suitably secured to the ceiling and floor as by nails, bolts, etc. Upon 45 each side of the plate-pieces are secured, as by staples, the metal studding which is composed of vertical metal studs or wires 3, arranged in parallel pairs, each pair connected at regular intervals, say at 8-inch 50 vertical intervals, by the short horizontal metal separators 4, which are preferably composed of metal wire somewhat smaller than studs 3.

The metal studding composed of studs 3 and horizontal separators 4, is practically 55 one structure, formed so by having the separators 4, united to the studs 3, as by welding, or the said parts may be riveted, tied, clinched, soldered, or woven together, or united in other substantial manner, so 60 that they may be built up in advance and brought to the work in a continuous length, or cut to length as desired.

It will be observed that the ends of the 65 separators 4 project somewhat outside the vertical plane of the studs 3. The object of this is to provide support for the metal lath 5, which is secured by bending the projecting ends of the separators up around the 70 V stiffeners.

The metal lath 5, 6, is here illustrated as 75 provided with stiffeners of V-shape in cross-section, which are attached to the rear of the lath, at vertical intervals corresponding to separators 4, with the point of the V directed against the vertical posts 3, and with the stiffener located above the separator 4, which projects through the lath and is bent up around the stiffener, forming 80 a secure anchorage for the lath. The stiffener and the projecting ends of the separator may be omitted, in which case the lath will be tied directly to the stud, as for instance, with No. 18 galvanized tie wire. Upon the foundation thus formed may be 85 located the ordinary coating or covering 7 of plaster, etc.

I have illustrated an embodiment of my 90 invention reduced to practice in one concrete form, but many of the parts illustrated may be changed in form or arrangement or equivalent devices substituted without departing from my invention. For instance the studs 3 may be flat or rectangular or other suitable shape in cross-section, and 95 this is also true of the separator. The distances between the parts in the studding will be adjusted to the requirements of the job and are shown only illustratively.

What I claim and desire to secure by Letters Patent is:

A construction for buildings and the like, comprising vertical studs arranged in two parallel rows spaced apart, with a stud in one row opposite a stud in the other row, 105 transverse horizontal separators secured

thereto and having an end projecting out-
side of said studs, a metal lathing and a
stiffener interposed between said lathing
and said studs providing a drying space,
said stiffener and metal lathing and studs
being secured together by said separator.

In testimony whereof, I have hereunto set

my hand in the presence of two subscribing
witnesses.

HENRY OLIVER.
